UNITED STATES PATENT OFFICE.

GEORGE W. TRAMBLEY, OF CHICAGO, ILLINOIS, ASSIGNOR OF ONE-THIRD TO JOHN W. FARLEY, OF CHICAGO, ILLINOIS.

JACK-TRUCK.

1,239,640.

Specification of Letters Patent. Patented Sept. 11, 1917.

Application filed February 23, 1917. Serial No. 150,384.

To all whom it may concern:

Be it known that I, GEORGE W. TRAMBLEY, a citizen of the United States, residing at Chicago, in the county of Cook and State 5 of Illinois, have invented certain new and useful Improvements in Jack-Trucks, of which the following is a specification.

This invention relates to hand trucks, and more particularly to jack trucks, which are 10 designed to both lift and transport a load. The principal object of the invention is to provide a truck which may be readily backed beneath a heavy piece of furniture, a machine, or any other article that is supported 15 by legs or otherwise from the floor, and, by a simple upward swing of the tongue, or like draft member, may be caused to lift and carry such article in a manner enabling the latter to be transported to any desired place 20 of deposit, and then lowered onto the floor, the truck being then withdrawn from beneath the load.

One practical form in which my invention may be embodied is illustrated in the 25 accompanying drawings, in which—

Figure 1 is a top plan view of the truck in load-carrying position, the tongue being broken off;

Fig. 2 is a longitudinal section on the line 30 2—2 of Fig. 1;

Fig. 3 is a detail section on the line 3—3 of Fig. 1;

Fig. 4 is a fragmentary side elevation of the rear portion of the truck;

Fig. 5 is a view, partly in side elevation and partly in longitudinal section, showing the truck in lowered or collapsed position; and

Fig. 6 is a front elevation of the truck as 40 it appears in Fig. 2.

The general frame construction of my improved truck is built and operates upon the principle of a parallel ruler. That is to say, it employs a pair of rectangular frames, the 45 upper of which, that carries the load, is mounted upon the lower through the agency of pivoted links, which maintain the two frames in parallelism in all positions. A tongue connected to one of the frames serves not only for draft purposes, but also as a lever to effect the expansion of the frames and the consequent raising of the upper frame, and a manually releasable automatic locking device secures the two frames in 55 fully expanded position the instant that po-

sition is reached in the frame-expanding operation. The connecting links of the frames are slightly off vertical in the fully raised position of the upper frame, so that when the lock is released the weight of the 60 load at once collapses the two frames. Suitable wheels or rollers are provided at the corners of the lower frame, the front wheels preferably being trailing casters for the purpose of easy steering. In the embodiment 65 of the invention herein shown, the side and end members of the lower frame are jointed through the agency of portions of the connecting links, but this does not affect the principle of the construction, which is capable of embodiment in a construction employing a rigid underframe. 70

Referring to the drawings, 10 designates the longitudinal side bars, 11 the rear cross bar, and 12 the front cross bar of the lower 75 frame, the side bars having a jointed connection with the rear cross bar 11 through the agency of the lower portions 13' of a pair of rear links 13, and the side bars having a jointed connection with the front cross 80 bar through the agency of upwardly extending portions 14' of a pair of front links 14. The upper or load-carrying frame, as herein shown, comprises a pair of parallel side bars 15 rigidly connected and spaced by intermediate transverse rods 16, and front and rear transverse end bars 17 and 18, respectively, the former extending between and rigidly secured in the forward links 14, and the latter extending between and rigidly secured in the rear links 13. The side bars 15 and their connecting rods 16 are preferably made removable from the end bars 17 and 18 by means of notches 19 in the lower sides of the bars 15 straddling said end bars 17 and 18 in the manner clearly shown in Fig. 3. 90

Mounted on axles 20 extending outwardly from the lower ends of the rear links 13 are wheels or rollers 21; while the forward links 14 are formed with laterally extending 100 flanges 22, on the under sides of which are suitably mounted trailing casters 23.

To lock the two relatively expandible and collapsible frames in expanded or load carrying position, I provide a pair of bars 24 that 105 are pivoted at 25 to the inner sides of the side bars 10 of the lower frame and, at their forward ends, are notched on their lower edges to provide hooks 26 that are adapted to engage the forward cross bar 17 of the 110

upper frame so as to hold said frames against relative movement toward each other. Preferably, and as herein shown, the free ends of the locking bars 24 are connected by a bail-shaped handle 27, which facilitates manual release of the locking bars when the load is to be lowered.

In order to render this locking device automatic upon the completion of the expanding movement of the two frames, I provide a tension spring 28, the upper end of which is connected to the handle 27, while its lower end is anchored to a short arm 29 that is fast on the cross bar 17.

In order to limit the expanding movement of the frames to an extent wherein the connecting links will be slightly off vertical, so as to insure the dropping of the load when the lock is released, I provide on either or both of the side bars 15, a stop lug or lugs 30 that are engaged by the upper ends of the links 13 just before the latter reach a vertical position. The downward or collapsing movement is limited by a pair of lateral pins or lugs 31, projecting from the upper ends of the links 13 and adapted to contact with the upper edges of the side bars 10 in the collapsed position of the frames, as clearly shown in Fig. 5.

Pivotedly connected at 32 to the forward links 14 is the hound 33 of a draft pole or tongue 34 that is provided at its outer end with an ordinary cross bar 35 forming a handle. Slidably mounted in brackets 36 on the upper side of the tongue 34 is a rod 37, the lower end of which is adapted to engage with an aperture 38 in the cross bar 12 in the fully-raised position of the tongue to support the latter in such position, as shown in Fig. 2; this rod being provided at its outer end with an operating handle 39.

The operation will be readily understood from the foregoing description, but may be briefly described as follows:

When a heavy article, such for instance as a stove, is to be transferred from one place to another, the jack truck, in the collapsed position illustrated in Fig. 5, is backed beneath the stove, and the tongue is then swung upwardly. During this movement, the hound portion of the tongue engages the forward cross bar 12 of the lower frame structure, and acts as a lever to rock the forward links 14 upwardly to the approximately vertical position shown in Fig. 2. A corresponding movement is imparted to the rear links 13 through the connecting side bars of the two frames; and, as soon as the cross rod 17 comes beneath the hooks 26 of the locking bars, the tension of the spring 28 instantly draws said hooks into engagement with the cross rod 17, and thereby locks the two frames in expanded position against the tendency of the weight of the load to collapse them. At the same time, the stop

prevents the links from swinging past a vertical position in the event of any failure of the locking bars to operate as described. A powerful leverage for lifting purposes is thus provided by the relatively long tongue 70 or pole 34. As soon as the article has been lifted onto the truck, the tongue can be lowered to usual draft position, and the load transported to any desired place of deposit. When this is reached, the operator 75 lowers the tongue to the ground or floor, as shown in Fig. 5, lifts the handle 27, thus releasing the lock, and the weight of the load instantly causes the frames to collapse, bringing the article into engagement with the floor through its legs or other supports, so that the truck may be readily drawn out from beneath the same.

It will be observed that as the truck collapses, the forward rod 17 carrying the anchorage arm 29 of the spring 28 turns in a counter-clockwise direction from the position shown in Fig. 2 to that shown in Fig. 5, thereby raising the lower end of the spring, and thus preventing unnecessary stretching 90 of the latter during the collapsing operation.

In Figs. 2 and 5, I have indicated in dotted lines a board or platform 40 which may be removably applied to the top of the upper skeleton frame for carrying small articles, when the truck is used simply as a transportation truck, said board or platform conveniently being provided on its under side with longitudinal cleats 41 formed with 100 notches 42 straddling the cross rods 16.

As the truck does not have a pivoted or swinging front axle, the provision of trailing casters at the forward corners of the truck enables the latter to be readily steered, 105 these casters being self-righting during the lifting or expanding movement of the truck.

It is believed that the foregoing description will make clear to those skilled in this art the construction, mode of operation, and advantages of the invention; and, without limiting myself to the precise details herein shown and described,—

I claim:

1. In a jack truck, the combination of two substantially parallel horizontal frames, links pivotally connecting the adjacent ends of said frames, wheels on the lower ends of said links, a tongue connected to one of said frames and serving, when lifted, to effect the expansion of said frames, and manually releasable automatic means for locking said frames in expanded position comprising a pair of locking bars pivoted to the side members of one frame and having hooks engageable with an element of the other frame, a handle-bar connecting said locking bars, and a spring connected to said handle bar and normally urging said hooks into locking position.

2. In a jack truck, the combination of two substantially parallel horizontal frames, links pivotally connecting the adjacent ends of said frames, wheels on the lower ends of said links, a tongue connected to one of said frames and serving, when lifted, to effect the expansion of said frames, and manually releasable automatic locking means for locking said frames in expanded position comprising a locking member pivoted to one of said frames and having hooking engagement with an element of the other frame, a tension spring connected at one end to said locking member, and a movable anchor member for the other end of said spring, said anchor member operating to decrease the tension of said spring as the frames are collapsed and to increase its tension as the frames are expanded.
- 10 3. In a jack truck, the combination of two substantially parallel horizontal frames, a pair of links pivotally connecting the rear ends of said frames, wheels on the lower ends of said links, a pair of links pivotally connecting the forward ends of said frames and having upwardly extended portions, one of said frames having a cross-bar rigidly connecting the upper ends of said last-named
- 15 links, wheels on the lower ends of said last-named links, a tongue pivoted to said last-named links and adapted, when swung upwardly, to coöperate as a lever with said cross-bar through direct engagement with the latter to effect the expansion of said frames, and means for automatically locking said frames in expanded position.
- 20 4. In a jack truck, the combination of two substantially parallel horizontal frames, a pair of links pivotally connecting the rear ends of said frames, wheels on the lower ends of said links, a pair of links pivotally connecting the forward ends of said frames and having upwardly extended portions, one of said frames having an apertured cross-bar rigidly connecting the upper ends of said last-named links, a tongue pivoted to said last-named links and adapted, when swung upwardly, to coöperate as a lever with said cross-bar to effect the expansion of said frames, means for automatically locking said frames in expanded position, and a locking rod slidably mounted on said tongue and adapted to enter the aperture of said cross-bar to hold said tongue in elevated position.

GEORGE W. TRAMBLEY.
